UNITED STATES PATENT OFFICE.

JAMES M. CRANMER, OF ROCKFORD, MICHIGAN.

REIN-HOLDER.

SPECIFICATION forming part of Letters Patent No. 350,121, dated October 5, 1886.

Application filed February 5, 1886. Serial No. 190,953. (No model.)

To all whom it may concern:

Be it known that I, JAMES M. CRANMER, a citizen of the United States, residing at Rockford, in the county of Kent and State of Michigan, have invented certain new and useful Improvements in Rein-Holders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a view in perspective of my invention as attached to dash-board of vehicle. Fig. 2 is a top or plan view. Fig. 3 is a side view.

Similar letters refer to similar parts.

20 The object of my invention is to furnish a simple, inexpensive, and effective device for holding reins, made of steel or other suitable material.

I describe the same as follows: To the clips 25 E E upon the shoulders E' E', I fasten the holder consisting of the shank D, having the bent top D', and being turned upward from the bottom, forming the spring G, the convex stem C' nearly meeting said shank at the top 30 and terminating in the outward-curved end C. So shaped the holder is nearly closed at the top, while the flaring ends act as guides slipping the reins into the holder to the point B, spreading slightly said shank and stem and 35 held by the reacting spring of said parts. The clips E E, of malleable iron or other suitable material, may usually be clinched upon the dash-board firmly without other fastening; but where the dash-board is made of wood, or 40 when necessary, the clip may be made with an eye to receive a screw. Said clips are made with the shoulders E' E' to permit of the bending over of the top of the shank D toward the dash-board.

45 In Fig. 1 A A represent the reins, and F the dash-board.

I am aware that previous to my invention a rein-holder has been constructed of a single strip or blank of spring metal, and comprising a spring-loop for the reception and retention of the reins, and a clamp formed with a series of slots to render the clamp elastic. Such construction, which is shown and described in the patent granted A. Lay, No. 230,557, dated July 27, 1880, I do not seek to claim, my invention being limited to a shank having the clips attached thereto by means of shoulders E', which permit the inner upper end of the shank to be turned inwardly against the dash-board, as shown at D', thereby permitting the reins to be readily and quickly inserted between the flaring or diverging upper ends of the shank, and preventing all possibility of the reins being inserted between the holder and dash-board as would otherwise be the case.

Another advantage of my holder over the construction shown in the patent of Lay, before referred to, is found in the fact that in the manufacture of the holder small strips and scraps of material can be utilized, while Lay's construction necessitates stamping the holder from sheets of metal, thus entailing the waste of considerable material.

Having thus described my invention, what I claim, and desire to secure by Letters Patent of the United States, is—

A rein-holder comprising a spring-shank, D, having its inner upper end, D', turned outwardly to bear against the dash-board, and 80 having its other end curved, as at C, the attaching-clips E, and the shoulders on said clips, as set forth.

In testimony whereof I affix my signature in presence of two witnesses.

JAMES M. CRANMER.
